ONE-HAND PADDLE

Algernon F. Flournoy, Monroe, La.

Application March 12, 1937, Serial No. 130,558

3 Claims. (Cl. 9—24)

My invention relates to paddles.

An object of my invention is to provide a paddle that may be manipulated with one hand.

Another object of my invention is to provide 5 a paddle with means to hang it from the human arm when the paddle is not in actual use.

In such activities as hunting and fishing from 10 boats it often becomes necessary to release one hand from a paddle to hold the gun or fishing pole, as the case may be. In such situations as this, I have had to paddle with one hand while holding an object with the other. As the wrist is not naturally suited to this kind of work, it soon tires. The wrist of the arm is too weak to permit 15 the full use of the arm muscles in a paddling operation when a conventional paddle is held by only one hand.

Out of the desire to overcome this wrist strain, which always accompanied this one hand paddling operation, I conceived of the invention of 20 a one hand paddle, forming the basis of the instant patent application.

In the accompanying drawing, forming a part 25 of this application and in which like numerals are employed to designate like parts throughout the same,

Fig. 1 is a plan view of a paddle embodying my invention shown as it is held in the operative position, and,

Fig. 2 is an end view of same paddle, shown 30 hanging from the arm when the paddle is not in use.

Figure 3 is a cross sectional view of the blade of the paddle;

Figure 4 is a cross sectional view of the handle 35 of the paddle where it joins the blade of the paddle;

Figure 5 is a cross sectional view of the handle of the paddle along the medial portion of its length;

Figure 6 is a cross sectional view of the handle 40 of the paddle at its end.

In the drawing wherein for the purpose of illustration is shown a preferred form of my 45 invention, numeral 1 designates generally the handle of the paddle. Numeral 2 designates the paddle's blade, and numeral 3 designates a semi-rigid strap attached to the handle 1. The strap is preferably made out of metal or other suitable material sufficiently yieldable to permit 50 manual adjustment to the arm. The strap 3 may be made out of any kind of stock that would present a smooth bearing surface to the arm, such as rods and tubes. For a matter of ease 55 and economy in manufacture, I have found that

flat metal strips of malleable iron and other ductile material are well suited for making these straps. It is this type of strap that is illustrated in the instant specification.

The paddle itself is preferably made of light 5 wood as this material is cheap and lends itself nicely to shaping. But it is to be understood that I may employ metal and the like in the construction of the paddle proper without departing from the scope of this invention. I am also 10 aware of the fact that the entire paddle, including the strap, could be cast as a unit. Various other methods of manufacture are within the purview of this disclosure.

When the strap 3 is formed from a flat strip 15 as disclosed by the instant specification, that portion of the length of the strap designed to contact the forearm should be curved lengthwise to fit the rounded form of the arm. The stock along this same bearing length should be curved 20 also crosswise of its length to assure a rounded bearing surface on the forearm, not only when the paddle is in the operative position as shown in Fig. 1 but also in the hanging position as shown by Fig. 2.

I found that a strap in the form of a hook, shown in Fig. 1 of the drawing, gave the best results as the opening in the hook type strap permitted the strap to be thrown over the arm after the paddle was picked up by the handle in 30 the normal way. I also found it advantageous to mount the strap on the end of the paddle as shown in Fig. 1 with the plane of the hook intersecting the center line of the handle at an angle greater than 90 degrees. By making the 35 angle greater than 90 degrees the effective entrance gape between the end of the strap and the handle was increased for a given vertical height between the inner surface of the strap and the surface of the handle. Another and 40 more important reason for mounting the strap at an angle greater than 90 degrees is to permit the paddle to hang in a nearly vertical position from the forearm when the paddle is not in use. By allowing the paddle to hang vertically from 45 the forearm freely, the paddle hand may be left free to assist the other hand in operations requiring the use of both hands.

In the operative position illustrated in Fig. 1, the strap 3 is shown extended over the fore- 50 arm above the wrist.

When a normal forward stroke down against the water is taken with the paddle as held in Fig. 1, the reaction of the water against the blade 2 of the paddle causes the handle 1 and 55

strap 3 to pivot through the hand as a fulcrum, thereby to bring the strap 3 down against the forearm. In this way the principal part of the force of the water reaction against the blade is transmitted directly to the forearm, thereby relieving the wrist of any strain.

It is to be understood that the foregoing description of my invention is to be taken for illustrated purposes only, and that various changes 10 in size and shape may be made within the scope of this invention, and that I am to be limited only by the scope of the claims to follow.

Having described my invention, I claim,

1. A paddle comprising a blade and a handle, 15 said handle being provided with a rigid hook

shaped strap member attached at one of its ends to the handle, thence extending in a curvilinear direction, upwardly and across the center line of the said handle, said strap member being adapted to brace a human arm.

2. The device as claimed in claim 1, wherein the said handle extends upwardly, rearwardly and across the center line of the handle.

3. A paddle comprising a blade, a handle extending from the blade and a rigid C shaped hook member attached to the handle on a side thereof and at the end remote from the blade, said hook member being of such length as to substantially encircle the wearer's wrist.
